UNITED STATES PATENT OFFICE.

LLOYD ESPENSCHIED, OF HOLLIS, NEW YORK, ASSIGNOR TO AMERICAN TELEPHONE AND TELEGRAPH COMPANY, A CORPORATION OF NEW YORK.

BALANCING ARRANGEMENT FOR MULTIPLEX CARRIER CIRCUITS.

Application filed September 26, 1919. Serial No. 326,520.

To all whom it may concern:

Be it known that I, LLOYD ESPENSCHIED, residing at Hollis, in the county of Queens and State of New York, have invented certain Improvements in Balancing Arrangements for Multiplex Carrier Circuits, of which the following is a specification.

This invention relates to signaling circuits and more particularly to arrangements 10 for balancing a transmission circuit at a plurality of frequencies.

One of the features of the invention resides in the provision of separate balancing arrangements, each adapted to balance a 15 transmission circuit at one frequency or a band of frequencies, of a number of frequencies or bands of frequencies utilized in multiplex transmission over said circuit.

Another feature of the invention relates 20 to the provision of separate networks each adapted to balance a transmission line at different frequencies, together with selective means whereby the transmission to the networks of frequencies other than those at 25 which they are adapted to balance the transmission circuit will be prevented.

Still another feature of the invention relates to the provision in a circuit of the character just described, of means associated with the transmission circuit for balancing the selective means associated with the networks.

Other and further features of the invention will more fully hereinafter appear from 35 the following description when read in connection with the accompanying drawing, Figures 1 to 5 of which constitute circuit diagrams of a number of embodiments of the invention.

Referring to Figure 1, ML designates a 40 transmission line or circuit over which a plurality of signals may be simultaneously transmitted by the use of carrier circuits of different frequencies. A common transmitting circuit T leading to individual transmitting channels (not shown) and a common receiving circuit R leading to individual receiving channels (not shown) are associated with the line ML through a balanced 45 transformer arrangement 10 of well-known construction. In order to balance the main line ML networks B₁, B₂ and B₃ are provided, these networks being connected in 50 parallel with each other. Each network as

illustrated consists of an inductance, capacity and resistance in series. By suitably adjusting the elements of the networks, as for instance the capacities and the resistances, each network may be made to offer the same impedance to one of three different 55 characteristic frequencies utilized in connection with the transmission of signals over the line ML, as is offered by the line ML itself to currents of that frequency. The resistance component of the impedance indicated as supplied by a variable resistance element may be resident in part or in whole in the dissipation of the inductance and capacity elements. It will therefore be seen that the line ML is balanced at the three 60 different frequencies utilized in the multiplex transmission of signals and while it is not properly balanced at other frequencies 65 this effect is of no consequence, since such other frequencies are not transmitted to the line. The use of a plurality of balancing circuits, as above described, has the advantage that it is possible to obtain a fairly accurate balance at the desired frequencies, even though the frequencies extend over a considerable range. If it were 70 desired to balance a line at all frequencies over the same range, by means of a single network, difficulty would be experienced in the design of a network which would simulate the electrical characteristics of the line over such a wide range, particularly in cases where the impedance characteristic of the line is not smooth, due for instance to an open wire line passing through sections of cable etc. 75

A modified arrangement is illustrated in Figure 2, in which the same principle is applied to a circuit adapted for the transmission of signaling bands of frequencies 80 of considerable width, as distinguished from the transmission of extremely narrow bands, such as contemplated in Figure 1. In Figure 2 the transmitting circuit T is provided with transmitting branches T₁, T₂, and T₃ over which different signaling bands may be transmitted to the line ML. In order to provide for frequency separation between the channels, filters such as F₁', F₂' and F₃' are inserted in the branches. 85 These filters may be of any well-known type, but are preferably broad band filters of the general type disclosed in the U. S. 90 95 100 105

patents to George A. Campbell, Nos. 1,227,-
113 and 1,227,114, dated May 22, 1917. In
a similar manner the receiving circuit R
is provided with a plurality of branches R₁,
5 R₂ and R₃ including the filters F₁, F₂ and
F₃ of a type similar to those described in
connection with the transmitting channel.

In order to balance the line ML, networks
10 B₁, B₂ and B₃ are provided. Each of these
networks may consist of a capacity and re-
sistance so adjusted that the network is
capable of balancing the line ML at a band
15 of frequencies corresponding to the fre-
quency band transmitted from one of the
transmitting channels T₁, T₂ or T₃. In
order to prevent transmission to the net-
work of frequencies other than those at
20 which it is designed to balance the line,
filters f₁', f₂' and f₃' are associated with
the networks B₁, B₂ and B₃ respectively, by
being serially included in the branches 1',
2' and 3', leading to the networks. These
25 filters may be of any type, but are prefer-
ably band filters of the type disclosed in
the patents to Campbell above referred to
and each filter may be similar to a corre-
sponding filter in a transmitting or receiv-
ing channel.

The inclusion of these filters in the net-
30 work renders desirable the provision of
similar apparatus in the line, consequently
the line ML is provided with three branches
1, 2 and 3, in which are included the net-
works f₁, f₂ and f₃. These networks may
35 be of any suitable structure adapted to
simulate the characteristics of the corre-
sponding filters in the circuits 1', 2' and 3'.
As illustrated, however, duplicated band
filters are employed for this purpose. The
40 filter networks on the line side may, how-
ever, be omitted without disturbing the bal-
ance, providing that the filters of the line-
balancing networks are designed to have
line impedance for the transmitted fre-
45 quency band.

As illustrated in Figure 2, the several
transmitting and receiving channels are as-
sociated with the main line through a com-
mon transformer 10. Figure 3 illustrates
50 a modified arrangement in which each
transmitting channel and a corresponding
receiving channel is associated with the
main line through a separate transformer.
In order to secure this result the branches
55 1, 2 and 3 are connected to branches 1',
2' and 3' by means of paths 111-111',
112-112' and 113-113', respectively. The
transmitting channel T₁ and receiving
channel R₁ are associated with the first of
60 these paths through a balanced transformer
arrangement 11. In a similar manner the
transmitting channel T₂ and the receiving
channel R₂ are associated through a bal-
anced transformer 12 with the second of
65 these paths and the transmitting channel T₃

and receiving channel R₃ are associated
with the third of these paths through the
transformer 13.

Selective filters may be provided in each
transmitting and receiving channel, if de-
70 sired, in the same manner as in Figure 2,
but, as illustrated, selectivity is obtained by
including filters F₁, F₂ and F₃ in paths 111,
112 and 113 respectively. These filters are
75 balanced on the network side by means of
duplicate filters or networks simulating the
characteristics of the filters, such as F₁', F₂'
and F₃'.

It will be observed that in the forms of
80 the invention illustrated in Figures 2 and 3
all of the network branches and other
branches of the circuit containing filters are
arranged in parallel with respect to each
other. It is possible, however, to secure the
85 same results by so relating all of these
branches that they will not only be in series
with respect to each other, but will also be
in series with respect to the main line ML
and the various balancing networks.

Figure 4 illustrates an arrangement of
90 the invention in which the circuit organiza-
tion of Figure 2 is modified in this man-
ner. Referring to this figure the transmit-
ting channels T₁, T₂ and T₃ are all serially
95 related to the common transmitting circuit
T and similarly the receiving channels R₁,
R₂ and R₃ are serially related to the com-
mon receiving circuit R. The circuits 1, 2
and 3 including the filters f₁, f₂ and f₃ are
100 serially related to each other and to the
main line ML. Similarly the circuits 1', 2'
and 3' containing the several networks and
the filters f₁', f₂' and f₃' are serially related
to each other and to the transformer 10.

Figure 5 illustrates a modification of the
105 circuit organization of Figure 3, in which
the branches are all serially related. Thus
the filters f₁, f₂ and f₃, as well as the filters
F₁, F₂ and F₃ are serially related to each
other and to the main line ML, while all
110 of the filters on the balancing side of the
circuit maintain a similar relation with re-
spect to each other.

It will be obvious that the general prin-
115 ciples herein disclosed may be embodied in
many other organizations widely different
from those illustrated, without departing
from the spirit of the invention as defined
in the following claims.

What is claimed is:

1. In a signaling system, a transmission
circuit, means whereby a plurality of sig-
nals may be simultaneously transmitted
over said circuit at a plurality of different
120 frequencies, balancing means for said trans-
mission circuit, comprising separate net-
works, each simulating the impedance of
said transmission line at one of said signal-
ing frequencies, band filters associated with
125 each network for preventing the transmis-
130

- sion to said network of other signaling frequencies and means associated with said transmission circuit for balancing said band filters.
5. 2. In a signaling system, a transmission circuit, means whereby a plurality of signals may be simultaneously transmitted over said circuit at a plurality of different frequencies, balancing means for said transmission circuit, comprising separate networks, each simulating the impedance of said transmission line at one of said signaling frequencies, selective means associated with each network for preventing the transmission to said network of other signaling frequencies, and selective devices associated with said transmission circuit, said selective devices being individually similar to the selective devices associated with said balancing networks and being associated with said transmission circuit in the same manner as the selective means associated with the balancing networks.
10. 3. In a signaling system, a transmission circuit, means whereby a plurality of different bands of frequencies may be simultaneously transmitted over said circuit, means for balancing said circuit, comprising networks each adapted to simulate the electrical characteristics of said circuit over one of said frequency bands, band filters associated with each network for preventing the transmission thereto of frequencies lying outside the band of frequencies at which the network is adapted to balance said transmission circuit, and means associated with said transmission circuit for balancing said band filters.
15. 4. In a signaling system, a transmission circuit, means whereby a plurality of different bands of frequencies may be simultaneously transmitted over said circuit, means for balancing said circuit, comprising networks each adapted to simulate the electrical characteristics of said circuit over one of said frequency bands, selective means associated with each network for preventing the transmission thereto of frequencies lying outside the band of frequencies at which the network is adapted to balance said transmission circuit, and means associated with said transmission circuit for balancing a plurality of individual selective devices similar to the selective devices associated with said networks and being related to said transmission circuit in a manner electrically equivalent to that in which the selective devices associated with said networks are related thereto.
20. 5. In a signaling system, a transmission circuit, balancing means for said transmission circuit comprising separate networks, each simulating the impedance of frequencies, a circuit arrangement for interconnecting said transmission circuit and said networks, a plurality of transmitting circuits and a plurality of receiving circuits associated with said connecting circuit arrangement, said transmitting and receiving circuits being arranged in pairs each pair corresponding to a band of frequencies to be transmitted to an individual network, and means associated with said connecting circuit arrangement on each side of said transmitting and receiving circuits to permit the transmission to each network of the band of frequencies at which the network simulates the impedance of the transmission circuit, while preventing the transmission of frequencies lying without said band.
25. 6. In a signalling system, a transmission circuit, balancing means for said transmission circuit comprising separate networks, each simulating the impedance of said transmission circuit over a different band of frequencies, a circuit arrangement for interconnecting said transmission circuit and said networks, a plurality of transmitting circuits and a plurality of receiving circuits associated with said connecting circuit arrangement, said transmitting and receiving circuits being arranged in pairs, each pair corresponding to a band of frequencies to be transmitted to an individual network, and band filters associated with said connecting circuit arrangement on each side of said transmitting and receiving circuits, said band filters transmitting to each network the band of frequencies at which it simulates the impedance of the transmission circuit while preventing the transmission of frequencies lying without said band.
30. 7. In a signalling system, a transmission circuit, balancing means for said transmission circuit comprising separate networks, each simulating the impedance of said transmission circuit over a different band of frequencies, branch circuits leading to each network, selecting means in each branch circuit for transmitting to the network the band of frequencies at which it simulates the impedance of the transmission circuit while suppressing frequencies lying without said band, corresponding branch circuits leading to the transmission circuit, selecting means in each of said last mentioned branch circuits leading to the transmission circuit, a circuit arrangement interconnecting the two sets of branches, and a plurality of transmitting and receiving circuits associated with said connecting circuit arrangement, said transmitting and receiving circuits being arranged in pairs corresponding to the bands of frequencies transmitted to the individual networks.
35. 8. In a signalling system, a transmission circuit, balancing means for said transmission circuit, comprising separate networks, each simulating the impedance of said transmission circuit over a different band of frequencies, a circuit arrangement for interconnecting said transmission circuit and said networks, a plurality of transmitting circuits and a plurality of receiving circuits associated with said connecting circuit arrangement, said transmitting and receiving circuits being arranged in pairs each pair corresponding to a band of frequencies to be transmitted to an individual network, and means associated with said connecting circuit arrangement on each side of said transmitting and receiving circuits to permit the transmission to each network of the band of frequencies at which the network simulates the impedance of the transmission circuit, while preventing the transmission of frequencies lying without said band.

- 4
- sion circuit comprising separate networks, each simulating the impedance of said transmission circuit over a separate band of frequencies, branch circuits leading to each network, band filters in each branch circuit for transmitting to the corresponding network, the range of frequencies at which said network simulates the impedance of the transmission circuit while suppressing frequencies lying without the band.
- 5 10 15 20 25 30 35 40 45 50 55
10. In a signalling system, a transmission circuit, balancing means for said transmission circuit comprising separate networks, each simulating the impedance of said transmission circuit over a different band of frequencies, branch circuits extending from each network to said transmission circuit, a transmitting circuit and a receiving circuit associated with each branch circuit and band filters in each branch circuit on either side of the transmitting and receiving circuits for transmitting to each network the band of frequencies at which said network simulates the impedance of the transmission circuit while suppressing the frequencies lying without said band.
9. In a signalling system, a transmission circuit, balancing means for said transmission circuit comprising separate networks, each simulating the impedance of said transmission circuit over a different band of frequencies, branch circuits extending from each network to said transmission circuit, a transmitting circuit and a receiving circuit

In testimony whereof, I have signed my name to this specification this 25th day of September, 1919.

LLOYD ESPENSCHIED.
